SAFETY GAS COCK

Louis Balazinski, East Port Chester, Conn.

Application December 19, 1929

Serial No. 415,371

2 Claims. (Cl. 158—117.1)

This invention relates to certain new and useful improvements in a safety gas cock and has for its primary object to provide a gas cock or valve construction embodying main and auxiliary valves with the auxiliary valve being unaffected or remaining in closed position upon opening movement of the main valve with manually and thermostatically operating devices associated with the auxiliary valve to provide for manual opening thereof and thermostatic closing should a flame be accidentally extinguished to prevent loss of life, resulting from asphyxiation.

With the above and other objects in view that will become apparent as the nature of the invention is better understood, the same consists in the novel form, combination and arrangement of parts hereinafter more fully described, shown in the accompanying drawing and claimed.

In the drawing:—

20 Figure 1 is a top plan view, partly in section of a safety gas cock and automatic gas burner constructed in accordance with the present invention;

25 Figure 2 is a vertical longitudinal sectional view showing the tensioned auxiliary valve in closed position with the manually and thermostatically operated devices associated therewith;

30 Figure 3 is a bottom view of the gas cock and thermostatic device.

Referring more in detail to the accompanying drawing, the reference numeral 1 designates a valve body or casing having an axial bore therethrough for the flow of gas with a transverse opening to receive the tapered valve 2 having a 35 transverse port 2a adapted to be brought into and out of registration with the bore of the casing. The head 2b of the valve is provided with an arrow indication 9 to designate the position of the transverse port 2a relative to the bore 40 of the valve casing. One end of the valve casing 1 is provided with a valve seat 1b to be engaged by a ball valve 4 that is moved onto its seat by the coil spring 5 which spring is retained in position in the bore by the cross pin 7 as shown 45 in Figure 2.

A plate 3 is slidably mounted upon the underside of the valve casing 1 and is bifurcated at one end to provide side legs 11 that straddle the adjacent end of the valve 2 that projects outwardly of the valve casing 1 and extend in an annular groove 2c in the projecting end of the valve. The end of the valve outwardly of the groove 2c is flattened on opposite sides to provide diametrically opposite lugs 2d adapted for engagement with the finger piece 10 depending from

the plate 3. The opposite end of the plate 3 carries an upwardly directed angle finger 2e that extends across the adjacent open end of the valve casing 1 in proximity to the valve seat 1b.

The valve casing 1 is set into one end of the burner 12 and the rod 14 longitudinally shiftable in the burner has the end thereof adjacent the valve casing slotted as at 15 to receive the angle finger 2e on the plate 3. The other end of the rod 14 is engaged with a thermostatic element 13 as 60 at 13b that is anchored as at 13a to the burner. As shown in Figures 1 and 2, the end of the rod 14 adjacent the valve casing extends into the open end of the casing for engagement with the ball valve 4. The connection 2e and 15 between 65 the plate 3 and rod 14 provides for lost motion of the rod to permit additional movement of the rod and thermostatic element without interference from the plate 3.

When the valve stem 2 is in its closed position 75 with the transverse port 2a extending transversely of the passage through the valve casing, the flattened sides of the projecting end of the valve stem project longitudinally of the valve casing, while the lug 2d is engaged with the finger piece 80 10 for the projection of the plate 3 so that the angle finger 2e on the end thereof is disposed relative to the slot 15 in the rod 14 to permit the spring 5 to move the ball valve 4 upon its seat 1b, this position being shown in Figure 2. 85 It is impossible to move the sliding plate 3 for unseating the ball valve 4 when the valve stem 2 is in its closed position. Upon opening the valve stem 2 to align the transverse port 2a thereof with the gas passage through the valve casing, the lug 2d upon the valve stem is displaced relative to the finger piece 10 while the ball valve 4 still remains upon its seat. Upon moving the plate 3, by the finger piece 10, the angle finger 2e moves the rod 14 into engagement with the ball 90 valve 4 to unseat the same against the tension of the spring 5, and the plate 3 is so held during ignition of the burner and for a period of time to permit the thermostatic element to assume the flexed position, and at which time the plate is 95 shifted to place the finger 2e in the opposite end of the slot 15 in the rod 14. The auxiliary valve 4 is maintained in its open position by the thermostatic element while the burner is in use, but should the flame become accidentally extinguished, the thermostatic element will assume a normal position and permit shifting movement of the rod 14 relative to the ball valve, being unhindered by the plate 3, to permit the ball valve 105 to be closed on its seat by the spring 5.

While there is herein shown and described the preferred embodiment of the present invention, it is nevertheless to be understood that minor changes may be made therein without departing from the spirit and scope of the invention as claimed.

I claim:—

1. In a thermostatic cut-off for gas burners, the combination with a valve structure embodying a manually operable main valve and an auxiliary valve tensioned in the direction of closing movement, of a plate slidably mounted on the valve structure and retained thereon by the main valve, a finger grip carried by the sliding plate, a thermostatic element responsive to heat of the burner, a slide rod positioned for operation at one of its ends by said thermostatic element with the other end positioned for engagement with the tensioned auxiliary valve, and a lost motion connection between the plate and rod to allow additional expansion of the thermostatic element without affecting movement of the plate.

2. In a thermostatic cut-off for gas burners, the combination with a valve structure embodying a manually operable main valve and an auxiliary valve tensioned in the direction of closing movement, of a plate slidably mounted on the valve structure and retained thereon by the main valve, a thermostatic element responsive to heat of the burner, a slide rod positioned for operation at one of its ends by said thermostatic element with the other end positioned for engagement with the tensioned auxiliary valve, and a pin and slot connection between the plate and rod permitting movement of the rod independently of the plate and said plate being manually operable for moving the rod into engagement with the auxiliary valve to open the same, and said thermostatic element normally occupying a position permitting shifting movement of the rod for closing movement of the tensioned auxiliary valve.
